HEEL-END LASTING MACHINE

Jacob C. Jorgensen, Beverly, Mass., assignor to
United Shoe Machinery Corporation, Flemington, N. J., a corporation of New Jersey

Application March 4, 1942, Serial No. 433,347

19 Claims. (Cl. 12—14)

This invention relates to machines for lasting the heel ends of shoes, and is herein illustrated as embodied in a modification of a machine constructed generally as disclosed in United States Letters Patent No. 2,059,241, granted on November 3, 1936 on an application of mine. It will be understood, however, that the invention is not thus limited in its applicability, but is susceptible of various embodiments.

A machine of the type illustrated in the above-mentioned Letters Patent is provided with wipers movable to wipe the margin of the heel end of an upper inwardly over an insole or other shoe bottom part on a last, a heel band which serves as an abutment for the heel-end face of the shoe and embraces the upper about the heel end of the last, a holddown for engaging the heel end of the insole to position the shoe and last heightwise in the lasting operation, and a jack for supporting the shoe and last, the jack including a heel-end support provided with a pin which enters the pinhole in the last and including also a toe rest which engages the top face of the toe end of the upper. The jack as a whole is mounted for rearward or inward swinging movement to carry the shoe lengthwise into engagement with the heel band and is provided with a post movable to carry the shoe heightwise into engagement with the holddown. The wipers receive two movements to wipe the upper inwardly over the insole, between which movements they are retracted from over the shoe. The jack is controlled in the power operation of the machine by two mechanisms which tend to swing it rearwardly, one of which acts on it yieldingly to press the heel-end face of the shoe against the heel band prior to the first operative movement of the wipers, and the other of which thereafter acts on it positively to press and hold the shoe more firmly against the band, the last-named mechanism including also means for operating the jack post to press the shoe heightwise against the holddown and means for closing the heel band against the sides of the shoe. The last-named mechanism receives two operative movements, one of which closely follows the operation of the above-mentioned yieldingly acting mechanism and the other of which occurs between the two operative movements of the wipers as the holddown rises to permit the shoe to be lifted slightly by the jack post prior to the second wipe.

In so far as both the above-mentioned mechanisms tend by their action on the jack to increase the pressure of the heel band on the heel-end face of the shoe, there is a tendency for the shoe

to be tipped in the direction to press its toe end more forcibly against the toe rest. An object of the present invention is to counteract or lessen the tendency thus to tip the shoe and thereby to avoid any such strain on a last in the shoe as might break a hinge last, especially if parts of the machine are not properly adjusted. With this in view, the construction herein shown is such that by the time substantial force is applied to the jack to press the heel-end face of the shoe against the heel band and wipers have begun to wipe the upper inwardly over the insole and are therefore in positions to counteract, by their pressure on the upper over the extreme end of the bottom of the shoe, the tendency to tip the shoe. As illustrated also the wipers, between their successive inward wiping movements, are not fully retracted from over the shoe, so that they are also in positions to counteract the tendency to tip the shoe when the shoe is pressed more firmly back against the heel band prior to the second wipe. With the above-mentioned object also in view, the construction shown is further such that positive control of the jack is postponed until just before the second wipe, prior to which time only the yieldingly acting mechanism tends to swing it rearwardly. This mechanism, moreover, acts to lessen somewhat the force with which the shoe is pressed rearwardly against the heel band as the wipers are partially retracted after the first wipe and become, therefore, less effective to prevent tipping of the shoe by reason especially of the fact that in the construction shown they are beveled on their upper-engaging faces adjacent to their wiping edges to conform better to the contour of the bottom of the last. As the heightwise movement of the shoe takes place upon retractive movement of the holddown, resulting in increased pressure of the wipers on the bottom of the shoe near the edge of the heel seat, the yieldingly acting mechanism again serves to increase the force with which the shoe is pressed rearwardly against the heel band, near the end of which operation the positively acting mechanism becomes effective further to increase this force and to lock the jack against any reverse swinging movement. In order to avoid any undue tendency for the wipers to resist the forcing of the shoe rearwardly, the construction shown is further such that the retractive movement of the holddown to permit the heightwise movement of the shoe prior to the second wipe is not completed until after the jack has been subjected to the full force tending to impart rearward movement to the shoe.

The above and other features of the invention will now be more particularly described with reference to the accompanying drawings and thereafter pointed out in the claims.

In the drawings,

Fig. 1 is a view partly in left-hand side elevation and partly in section of a portion of a machine in which the invention is embodied, the machine being one of the type disclosed in the previously mentioned Letters Patent;

Fig. 2 is a section on the line II—II of Fig. 1 on an enlarged scale;

Fig. 3 is mainly a plan view showing the wipers and portions of their operating mechanisms, with the wipers in their starting positions;

Fig. 4 is a view partly in left-hand side elevation and partly in section, showing mechanism provided for yieldingly controlling the jack;

Fig. 5 is a view similar to Fig. 4 showing additional mechanism provided for positively controlling the jack and for also operating the jack post and the heel band;

Fig. 6 is a plan view illustrating the relation of the wipers to the shoe at the end of their first inward wiping movements;

Fig. 7 is a view similar to Fig. 6, with parts broken away, illustrating the relation of the wipers to the shoe at the end of their retractive movements between the first and second wipes;

Fig. 8 is a view partly in left-hand side elevation and partly in section, showing the shoe and parts closely associated therewith at the same stage of the cycle of operations as in Fig. 7;

Fig. 9 is a view in left-hand side elevation showing mainly the cams for operating various parts of the machine;

Fig. 10 is a cross-sectional view of one of the wipers and associated parts; and

Fig. 11 is a cam chart illustrating the relative timing of different operations performed by the machine.

In view of the disclosure in the above-mentioned Letters Patent, the present description will be confined to such portions of the machine as it is necessary to refer to for an understanding of this invention. The machine is provided with a heel band 2 for embracing and clamping the upper about the heel end of the last, wipers 4 for wiping the marginal portion of the heel end of the upper inwardly over an insole or other shoe bottom part comprehended herein by the use of the term insole, means not herein particularly described, but shown partially in Figs. 8 and 10, for driving tacks through openings in the wipers to fasten the upper in lasted position, and a holdown 6 for engaging the heel end of the insole to determine the position of the shoe and last heightwise in the lasting operation. The shoe and last, hereinafter commonly referred to inclusively as the shoe, are supported on a jack 8 mounted at its lower end for rearward or inward swinging movement to carry the shoe lengthwise into position to be embraced by the heel band 2 and for pressing its end face against the band. The jack includes a heel pin 10 arranged to enter the usual spindle hole in the heel end of the last, the pin being fast on a block 12 on which is mounted a member 14 arranged for supporting engagement with the top face of the cone of the last. The block 12 is mounted on a post 16, and clamped on this post is a bar 18 which carries a toe rest 20 arranged for supporting engagement with the top face of the toe end of the shoe.

The post 16, which supports the shoe as above described, is slidingly mounted for upward and downward movements in a holder 22 mounted on pins 24 for limited swinging movements in directions widthwise of the shoe relatively to a jack casting 26 which supports the pins and the holder. By means fully described in the above-mentioned Letters Patent the post 16 is supported at its lower end on a rod 28 movable upwardly and downwardly in the casting 26 and having on its upper end a flange 30 which by engagement with the casting limits downward movement of the post. Upward movement of the rod 28 serves to impart upward movement to the post and the shoe and thus to force the shoe against the holdown 6. For this purpose the rod is connected to a slide 32 movable upwardly and downwardly in the lower end portion of the casting 26. When the shoe is first mounted on the jack, however, the jack is in a forwardly inclined position, as shown in Fig. 1, and it must be swung rearwardly to carry the heel end of the shoe to a position under the holdown 6 before the shoe is moved upwardly into engagement with the holdown.

In the machine herein shown, like that shown in the previously mentioned Letters Patent, such rearward swinging movement of the jack and also the upward movement of the post 16 to carry the shoe into engagement with the holdown are effected by the operator prior to the starting of the power operation of the machine. For this purpose there is provided a treadle 34 pivoted at 36 on the frame and connected by a link 38 to one arm of a lever 40 fulcrumed at 42 on a bracket 44 on the lower end of the jack casting 26. The other arm of the lever 40 engages the lower end face of the slide 32. Accordingly, by depression of the treadle 34 the slide 32 and the post 16 may be moved upwardly, and by reason of the relation of the link 38 to the fulcrum 42 of the lever 40 the depression of the treadle also serves to impart rearward swinging movement to the jack. While depressing the treadle the operator may press downwardly on the shoe to insure that the shoe will not be forced upwardly against the holdown 6 until after the rearward swinging movement of the jack by the treadle has been substantially completed.

After the starting of the power operation of the machine the jack is controlled automatically. For controlling it with respect to swinging movement there is provided a rack bar 46 pivotally connected to a pair of upwardly extending arms 48 of the jack casting 26, only one of these arms being visible in the drawings. The rack bar is slidingly mounted in a holder 50 which is mounted to turn about a shaft 52 as required by the swinging movements of the jack. The teeth of the rack bar 46 are engaged by a pinion 54 fast on the shaft 52. For controlling the jack through this shaft there are provided two different mechanisms shown respectively in Figs. 4 and 5, these mechanisms being constructed for the most part substantially as heretofore, but being operated in differently timed relation to each other for purposes of this invention, as more particularly hereinafter described. The mechanism shown in Fig. 4 is for the purpose of operating the jack in a yieldable manner to press the shoe rearwardly against the heel band. It comprises a ratchet wheel 56 which is keyed to the shaft 52 and is operated by one or the other of two spring-pressed pawls 58 pivotally mounted on a pawl carrier 60 rotatable about the axis of the shaft.

A control disk or shield 62 adjustable about the shaft 52 is arranged to release the pawls 58 to permit them to engage the ratchet wheel 56 at a variably predetermined time in the movement of the pawl carrier 60. It may be assumed that, consistently with the objects of the invention, the pawls are thus released substantially at the beginning of the movement of the pawl carrier. The pawl carrier is operated through a rod 64 by a lever 66 which is mounted to swing about a pin 68 on the frame. The rod 64 extends through a pin 70 which is swiveled in the lower arm of the lever 66 and is engaged on one side by a flange 72 on the rod and on the other side by a member 74 slidably mounted on the rod. Between this member and another member 76 which is held on the rod by nuts 78 is a compression spring 80. When the lever 66, therefore, is swung in a clockwise direction (Fig. 4) it acts yieldingly through the spring 80 to turn the pawl carrier 60 and thus through the pawls 58 and the ratchet wheel 56 to turn the shaft 52 in the direction to force the shoe more firmly back against the heel band by the swinging of the jack. For operating the lever 66 there is provided a slide 82 having rack teeth 84 in engagement with teeth on the upper arm of the lever, this slide carrying a roll 86 engaged by a path cam 88 (Fig. 9) formed in a cam drum 90 with which the machine is provided.

The mechanism shown in Fig. 5 is for the purpose, among others, of positively controlling the jack with respect to swinging movement after it has been yieldingly operated upon by the mechanism shown in Fig. 4. It comprises a ratchet wheel 92 which is fast on the shaft 52 and is operated by one or the other of two spring-pressed pawls 94 pivotally mounted on a pawl carrier 96 rotatable about the axis of the shaft. A control disk or shield 98, like the disk 66 shown in the previously mentioned Letters Patent, is adjustable about the shaft 52 and is arranged to release the pawls 94 to permit them to engage the ratchet wheel 92 at a variably predetermined time in the movement of the pawl carrier 96. Operative movement is imparted to the pawl carrier by an arm 100 which is integral with a sleeve 102 a portion only of which is visible in Fig. 5, this sleeve being mounted to turn about a rod 104 on the frame. The arm 100, instead of being connected directly to the pawl carrier 96 by a link as in the construction shown in the previously mentioned Letters Patent, is connected thereto by means so designed as to reduce the strain on the parts hereinafter described whereby the arm is operated. This means comprises a link 106 pivotally connected at its upper end to the arm 100 and pivotally connected at its lower end to one arm of a bell-crank lever 108 mounted on a fulcrum on the frame, the other arm 110 of this bell-crank lever being connected by a link 112 to the pawl carrier 96. This arm and the link 112 serve as a toggle which approaches a straightened position as the pawl carrier 96 is turned about the axis of the shaft 52 by the upward movement of the arm 100. It is through this toggle, therefore, that the force is applied positively to the jack with a tendency to swing it rearwardly, and accordingly less power is required to operate the arm 100 than if the arm were connected directly to the pawl carrier 96. For operating the arm 100 there is provided a member 114 mounted to turn about the rod 104 and having an arm 116 provided with a pin 118 arranged to engage the upper face of a lug 120 formed on a block 122 which is fast on the sleeve member 102, as more fully

explained in the previously mentioned Letters Patent. Rotation of the member 114, therefore, in a counterclockwise direction (Fig. 5) serves to swing the arm 100 in an upward direction to control the jack as above described. The member 114 is thus operated through a link 124 by a lever 126 to which movement is imparted by a rack bar 128 fast on a horizontal slide 130. This slide carries a roll 132 engaged by a path cam 134 (Fig. 9) formed in the drum 90.

The mechanism shown in Fig. 5 serves further, as heretofore, to control the jack post 16 by the upward movement of which the shoe is pressed against the holdown 6 and also to operate mechanism for closing the heel band 2 about the heel end of the shoe. For such control of the post there is provided a lever 136 (Fig. 1) which is fulcrumed on a rod 138 and carries at its front end a roll 140 lying in a slot in the previously mentioned slide 32. At its rear end the lever carries a curved rack bar 142 in engagement with a pinion 144 which is mounted to turn on a fixed rod 146 and is formed integral with a ratchet wheel 148. This ratchet wheel is engaged and turned in a counterclockwise direction (Fig. 1) by one or the other of two spring-pressed pawls 150 supported on a pawl carrier 152 which is mounted to turn about the rod 146. Associated with the pawls is a control disk 154 which releases the pawls for engagement with the ratchet wheel after a variably determined amount of initial movement of the pawl carrier 152, the control disk being adjustable about the rod 146 to vary the time in the movement of the pawl carrier when the pawls are thus released. When the pawls thus become effective on the ratchet wheel they serve to force the shoe more firmly up against the holdown and later to lift the shoe concurrently with an upward movement of the holdown, as more fully hereinafter explained. The pawl carrier 152 is operated by an arm 156 (Fig. 5) which is integral with the previously mentioned sleeve member 102 and therefore is moved upward simultaneously with the arm 100. The arm 156 is connected to the pawl carrier by a yieldable link 158 comprising a rod 160, a spring 162 and another rod 164. The rod 160 is pivotally connected at its upper end to the arm 156 and is provided at its lower end with a disk 166 in engagement with the lower end of the spring 162. Surrounding the spring 162 is a housing 168 which is connected by the rod 164 to the pawl carrier 152 and which serves as an abutment for the upper end of the spring. It will thus be seen that when the rod 160 is moved upwardly it acts through the spring 162 to operate the pawl carrier and that the spring may yield in response to resistance of the holdown 6 to upward movement of the shoe.

As above suggested, the mechanism shown in Fig. 5 serves also to close the heel band 2 about the heel end of the shoe. For this purpose a gear sector 170 (Fig. 1) is formed integral with the previously mentioned sleeve member 102 (Fig. 5) and serves to impart rearward movement to a slide 172 which corresponds to the slide 324 shown in the previously mentioned Letters Patent. In this movement the slide 172 acts yieldingly through a spring 174 to operate mechanism not herein shown but fully disclosed in the above-mentioned Letters Patent for closing the heel band yieldingly inward against the sides of the shoe.

The wipers 4 are supported on wiper carriers

176 (Fig. 3) which are mounted on a slide 178 movable forwardly and rearwardly along guideways 180 on the frame. The wiper carriers 176 are guided for swinging movements laterally of the shoe to close the wipers inwardly over the bottom of the shoe by a groove 182 in the slide 178. The slide 178 is moved forwardly to advance the wipers lengthwise of the shoe by a path cam 184 in the drum 90, this cam engaging a roll 186 on the slide. For closing the wipers laterally of the shoe there are pivotally connected to the wiper carriers 176 links 188 each of which has threaded in its rear end a member 190 connected by a pin 192 to a rack bar 194 mounted in a guideway in the frame. The teeth of each rack bar are engaged by the teeth of a gear sector 196 formed on a member 198 which is rotatable about a pin 200 and has teeth 202 in engagement with teeth on a central rack bar 204 secured to a slide 206 movable in guideways in the frame. The slide 206 carries a roll 208 engaged by a path cam 210 in the drum 90. Accordingly, rearward movement of the slide 206 effected by the cam 210 serves to impart forward movements to the rack bars 194 and the links 188 and thus to close the wipers laterally of the shoe while they are advanced bodily lengthwise of the shoe by forward movement of the slide 178. From their wiping edges outwardly the wipers are beveled on their lower faces, as shown at 212 (Fig. 10), to conform approximately to the usual slope of the bottom face of the heel end of a last near the edge of the last bottom.

The holdown 6 is vertically movable and is controlled as heretofore by a face cam 214 (Fig. 9) on the front end of the drum 90 through mechanism constructed as shown in the previously mentioned Letters Patent and which need not be herein described in detail.

The manner of operation of the machine, in so far as it is of interest with reference to the present invention, will now be briefly described with particular reference to the cam chart (Fig. 11). It should be understood that on this chart the designation "Jack swing" refers to the cam 88 for operating the yieldingly acting mechanism shown in Fig. 4 and the designation "Jack and heel band" refers to the cam 134 for operating the mechanism shown in Fig. 5. After mounting the shoe on the jack the operator depresses the treadle 34 to swing the jack rearwardly and to raise the jack post 16, thereby presenting the shoe in engagement with the heel band 2 and the holdown 6 in the same manner as heretofore, after which he starts the power operation of the machine. Substantially at the beginning of the operation of the machine downward movement is imparted to the holdown to depress the shoe to the proper level for the first wiping action of the wipers. In the course of this movement of the holdown the mechanism shown in Fig. 5 becomes operative to close the heel band inwardly against the sides of the shoe and by control of the jack post 16 through the spring 162 to press the shoe yieldingly upward against the holdown, this mechanism completing its movement after the downward movement of the holdown has ceased and after the advancing and closing movements of the wipers have begun. During the operation of this mechanism the pawls 94 are still supported by the shield 98 out of engagement with the ratchet wheel 92 and therefore do not become effective to control the jack with respect to swinging movement. By the time the wipers arrive in positions to begin to

wipe the margin of the upper inwardly over the insole the yieldingly acting mechanism shown in Fig. 4 becomes effective on the jack to press the shoe rearwardly against the heel band and to prevent it from being moved forwardly by the wipers. Before any very substantial pressure is applied by the heel band to the heel-end face of the shoe in this operation the wipers have moved far enough to overlap more or less the bottom of the shoe at its extreme end and thus to counteract any tendency that there may be for the heel band to tip the shoe in the direction to depress its toe end supported by the toe rest 20. The movement of the mechanism shown in Fig. 4 continues until the wipers have substantially completed their inward wiping movements, so that the pressure of the heel band on the heel-end face of the shoe increases substantially throughout the inward wipe. The wipers are then partially retracted and opened preparatory to a second inward wipe, but are not fully withdrawn from over the extreme end of the shoe bottom, as shown in Fig. 7, so that they still oppose any tendency for the heel band to tip the shoe. In view, however, of the fact that the wipers, especially by reason of the bevel 212 (Fig. 10) adjacent to their wiping edges, are not so effective to prevent tipping of the shoe when they have thus been retracted to the positions shown in Fig. 7 as when they are fully over the heel seat, the jack-controlling mechanism shown in Fig. 4 is moved reversely to lessen somewhat the pressure of the heel band on the heel-end face of the shoe during the above-mentioned retractive movements of the wipers.

Shortly after the end of the retractive movements of the wipers the cam 214 controlling the holdown becomes effective to permit an upward movement of the holdown, so that the shoe, together with the heel band, may be lifted by the jack post 16 to a somewhat higher level preparatory to the second wipe, the bevel on the wipers permitting the shoe to receive sufficient upward movement for the purpose in view even though the wipers are still over the extreme end of the heel seat. At approximately the same time the mechanism shown in Fig. 4 is again operated to increase the force tending to swing the jack rearwardly and thereby to increase the pressure of the heel band on the heel-end face of the shoe, the wipers becoming more effective by reason of the raising of the shoe to counteract any tendency to tip the shoe. As indicated by the chart, however, upward movement of the holdown is not completed until shortly after the completion of the operation of the mechanism shown in Fig. 4, in order to prevent the pressure of the wipers on the end of the shoe from interfering unduly with the pressing of the shoe as firmly as desired rearwardly against the heel band. As the holdown is thus permitted to rise, the mechanism shown in Fig. 5 becomes effective to apply increased upward force to the jack post 16 and to close the heel band more firmly inward against the sides of the shoe, and near the end of the movement of this mechanism the pawls 94 are released by the shield 98 and become effective on the ratchet wheel 92 to apply to the jack positive force tending to swing it rearwardly and to lock it against any forward movement preparatory to the second wipe. This action of the pawls also takes place before the holdown has completed its upward movement. The wipers are then moved inwardly the second time, and when at the end of their inward movements the

tacks are driven as heretofore to fasten the margin of the upper in lasted position. Thereafter the parts of the machine are returned to their starting positions in substantially the same time relation to one another as heretofore.

Having described the invention, what I claim as new and desire to secure by Letters Patent of the United States is:

1. In a heel-end lasting machine, wipers movable to wipe the margin of the heel end of a shoe upper inwardly over an insole on a last, means for operating said wipers, an abutment arranged to engage the heel-end face of the shoe, a shoe support, and automatic means for effecting relative movement of said shoe support and abutment in a direction lengthwise of the shoe to cause the abutment to apply pressure to the heel-end face of the shoe, the operation of said automatic means being so timed relatively to the operation of the wipers as to cause substantial pressure to be applied by the abutment to the heel-end face of the shoe only after the wipers have been begun to wipe the margin of the upper inwardly over the insole.

2. In a heel-end lasting machine, wipers movable to wipe the margin of the heel end of a shoe upper inwardly over an insole on a last, means for operating said wipers, an abutment arranged to engage the heel-end face of the shoe, a shoe support movable in directions lengthwise of the shoe, and automatic means for operating said shoe support to force the heel-end face of the shoe against said abutment with substantial pressure only after the wipers have begun to wipe the margin of the upper inwardly over the insole.

3. In a heel-end lasting machine, wipers movable to wipe the margin of the heel end of a shoe upper inwardly over an insole on a last, means for operating said wipers, an abutment arranged to engage the heel-end face of the shoe, a shoe support movable in directions lengthwise of the shoe, and automatic means for yieldingly operating said shoe support to force the heel-end face of the shoe against said abutment with substantial pressure only after the wipers have begun to wipe the margin of the upper inwardly over the insole and thereafter to increase said pressure substantially throughout the remainder of the inward wipe on the upper.

4. In a heel-end lasting machine, wipers movable to wipe the margin of the heel end of a shoe upper inwardly over an insole on a last, means for operating said wipers, an abutment arranged to engage the heel-end face of the shoe, a shoe support, and automatic means movable independently of said wiper-operating means but in predetermined time relation thereto for effecting relative movement of said shoe support and abutment in a direction lengthwise of the shoe to cause the abutment to apply to the heel-end face of the shoe pressure increasing substantially throughout the inward wipe on the upper.

5. In a heel-end lasting machine, wipers movable to wipe the margin of the heel end of a shoe upper inwardly over an insole on a last, means for operating said wipers, an abutment arranged to engage the heel-end face of the shoe, a shoe support movable in directions lengthwise of the shoe, and automatic means for yieldingly operating said shoe support to force the heel-end face of the shoe against said abutment with pressure increasing substantially throughout the inward wipe on the upper.

6. In a heel-end lasting machine, wipers movable to wipe the margin of the heel end of a shoe upper inwardly over an insole on a last, means for operating said wipers thus to wipe the margin of the upper inwardly and for then partially retracting them from over the shoe, an abutment arranged to engage the heel-end face of the shoe, a shoe support, and automatic means for effecting relative movement of said shoe support and abutment in a direction lengthwise of the shoe to cause the abutment to apply substantial pressure to the heel-end face of the shoe only after the wipers have begun to wipe the margin of the upper inwardly over the insole and for thereafter reducing said pressure as the wipers are partially retracted.

7. In a heel-end lasting machine, wipers movable to wipe the margin of the heel end of a shoe upper inwardly over an insole on a last, means for operating said wipers thus to wipe the margin of the upper inwardly and for then partially retracting them from over the shoe, an abutment arranged to engage the heel-end face of the shoe, a shoe support movable in directions lengthwise of the shoe, and automatic means for yieldingly operating said shoe support to force the heel-end face of the shoe against said abutment as the upper is wiped inwardly by the wipers and for thereafter reducing the pressure of the heel-end face of the shoe on the abutment as the wipers are partially retracted.

8. In a heel-end lasting machine, wipers movable to wipe the margin of the heel end of a shoe upper inwardly over an insole on a last, means for operating said wipers thus to wipe the margin of the upper inwardly and for then partially retracting them from over the shoe, an abutment arranged to apply pressure to the heel-end face of the shoe, and automatic means for reducing the pressure of said abutment on the heel-end face of the shoe as the wipers are thus partially retracted.

9. In a heel-end lasting machine, wipers movable to wipe the margin of the heel end of a shoe upper inwardly over an insole on a last, means for operating said wipers thus to wipe the margin of the upper inwardly and for then partially retracting them from over the shoe preparatory to a second inward wipe, means for increasing the pressure of the wipers on the upper heightwise of the shoe after they have thus been partially retracted, an abutment arranged to apply pressure to the heel-end face of the shoe, and automatic means for reducing the pressure of said abutment on the heel-end face of the shoe as the wipers are partially retracted and for thereafter increasing said pressure in time relation to the increase of pressure of the wipers on the upper heightwise of the shoe.

10. In a heel-end lasting machine, wipers movable to wipe the margin of the heel end of a shoe upper inwardly over an insole on a last, means for operating said wipers thus to wipe the margin of the upper inwardly and for then partially retracting them from over the shoe preparatory to a second inward wipe, means for increasing the pressure of the wipers on the upper heightwise of the shoe after they have thus been partially retracted, an abutment arranged to engage the heel-end face of the shoe, a shoe support movable in directions lengthwise of the shoe, and automatic means for controlling said shoe support to force the heel-end face of the shoe against said abutment as the upper is wiped inwardly by the wipers, to reduce the pressure of the heel-end

face of the shoe on the abutment as the wipers are partially retracted, and thereafter to increase said pressure in time relation to the increase of pressure of the wipers on the upper heightwise of the shoe.

11. In a heel-end lasting machine, wipers movable to wipe the margin of the heel end of a shoe upper inwardly over an insole on a last, means for operating said wipers twice to wipe the margin of the upper inwardly and for retracting them between the two inward wipes, an abutment arranged to press on the heel-end face of the shoe, and automatic means for twice increasing the pressure of said abutment on the heel-end face of the shoe in time relation to the two inward wipes on the upper respectively and for reducing said pressure between the two inward wipes.

12. In a heel-end lasting machine, wipers movable to wipe the margin of the heel end of a shoe upper inwardly over an insole on a last, means for operating said wipers twice to wipe the margin of the upper inwardly and for retracting them between the two inward wipes, an abutment arranged to engage the heel-end face of the shoe, a shoe support, and automatic means for effecting relative movement of said shoe support and abutment in the course of the first inward wipe to cause the abutment to apply pressure to the heel-end face of the shoe, for reducing said pressure as the wipers are retracted, and for increasing said pressure in time relation to the second inward wipe.

13. In a heel-end lasting machine, wipers movable to wipe the margin of the heel end of a shoe upper inwardly over an insole on a last, means for operating said wipers twice to wipe the margin of the upper inwardly and for partially retracting them from over the shoe between the two inward wipes, means for increasing the pressure of the wipers on the upper heightwise of the shoe after they have thus been partially retracted, an abutment arranged to engage the heel-end face of the shoe, a shoe support, and automatic means for effecting relative movement of said shoe support and abutment in the course of the first inward wipe on the upper to cause the abutment to apply pressure to the heel-end face of the shoe, for reducing said pressure as the wipers are partially retracted, and for thereafter increasing said pressure preparatory to the second inward wipe.

14. In a heel-end lasting machine, wipers movable to wipe the margin of the heel end of a shoe upper inwardly over an insole on a last, means for operating said wipers twice to wipe the margin of the upper inwardly and for partially retracting them from over the shoe between the two inward wipes, an abutment arranged to engage the heel end face of the shoe, a shoe support movable in directions lengthwise of the shoe, automatic means movable to force the heel-end face of the shoe more firmly against said abutment by control of said shoe support after the wipers have been partially retracted from over the shoe, a holdown arranged to engage the bottom of the heel end of the shoe and movable to permit the shoe to be urged heightwise toward the wipers after the wipers have thus been partially retracted, and means for thus urging the shoe toward the wipers through the shoe support, the movement of said holdown being so timed as to terminate after the completion of the movement of said automatic means for forcing the shoe more firmly against the abutment.

15. In a heel-end lasting machine, wipers movable to wipe the margin of the heel end of a shoe upper inwardly over an insole on a last, means for operating said wipers twice to wipe the margin of the upper inwardly and for partially retracting them from over the shoe between the two inward wipes, an abutment arranged to press on the heel-end face of the shoe, a shoe support movable in directions lengthwise of the shoe, and automatic means for yieldingly controlling said shoe support to increase twice the pressure of said abutment on the heel-end face of the shoe in time relation to the two inward wipes on the upper respectively and to reduce said pressure between the two inward wipes.

16. In a heel-end lasting machine, wipers movable to wipe the margin of the heel end of a shoe upper inwardly over an insole on a last, means for operating said wipers twice to wipe the margin of the upper inwardly and for partially retracting them from over the shoe between the two inward wipes, an abutment arranged to engage the heel-end face of the shoe, a shoe support movable in directions lengthwise of the shoe, and automatic means for yieldingly controlling said shoe support to force the heel-end face of the shoe against said abutment in the course of the first inward wipe on the upper, to reduce the pressure of the abutment on the heel-end face of the shoe as the wipers are partially retracted, and to increase said pressure in time relation to the second inward wipe.

17. In a heel-end lasting machine, wipers movable to wipe the margin of the heel end of a shoe upper inwardly over an insole on a last, means for operating said wipers twice to wipe the margin of the upper inwardly and for retracting them between the two inward wipes, an abutment arranged to engage the heel-end face of the shoe, a shoe support movable in directions lengthwise of the shoe, automatic means for yieldingly controlling said shoe support to cause said abutment to press on the heel-end face of the shoe as the upper is first wiped inwardly by the wipers, and additional automatic means for positively controlling the shoe support only after the first inward wipe on the upper to maintain pressure of said abutment on the heel-end face of the shoe during the second inward wipe.

18. In a heel-end lasting machine, wipers movable to wipe the margin of the heel end of a shoe upper inwardly over an insole on a last, means for operating said wipers twice to wipe the margin of the upper inwardly and for retracting them between the two inward wipes, an abutment arranged to engage the heel-end face of the shoe, a shoe support movable in directions lengthwise of the shoe, automatic means for yieldingly controlling said shoe support to cause said abutment to press on the heel-end face of the shoe as the upper is first wiped inwardly by the wipers, and additional automatic means for positively controlling the shoe support only after the wipers have thus been retracted to increase the pressure of said abutment on the heel-end face of the shoe and to maintain the increased pressure during the second inward wipe.

19. In a heel-end lasting machine, wipers movable to wipe the margin of the heel end of a shoe upper inwardly over an insole on a last, means for operating said wipers twice to wipe the margin of the upper inwardly and for partially retracting them from over the shoe between the two inward wipes, an abutment arranged to en-

gage the heel-end face of the shoe, a shoe support movable in directions lengthwise of the shoe, automatic means for yieldingly controlling said shoe support to force the heel-end face of the shoe against said abutment in the course of the first inward wipe on the upper, to reduce the pressure of said abutment on the heel-end face of the shoe as the wipers are partially retracted,

and to increase said pressure preparatory to the second inward wipe, and additional automatic means for positively controlling the shoe support only after the first inward wipe to maintain the pressure of said abutment on the heel-end face of the shoe during the second inward wipe.

JACOB C. JORGENSEN.

CERTIFICATE OF CORRECTION.

Patent No. 2,328,075.

August 31, 1943.

JACOB C. JORGENSEN.

It is hereby certified that error appears in the printed specification of the above numbered patent requiring correction as follows: Page 1, second column, line 11, for "and" read --the--; page 4, second column, line 75, after "when" insert --they are--; page 5, first column, line 23, claim 1, strike out "been"; and that the said Letters Patent should be read with this correction therein that the same may conform to the record of the case in the Patent Office.

Signed and sealed this 7th day of December, A. D. 1943.

(Seal)

Henry Van Arsdale,
Acting Commissioner of Patents.
